UNITED STATES PATENT OFFICE.

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA.

CAR ROOF.

Application filed April 21, 1926. Serial No. 103,424.

Heretofore single course car roofs have been made wherein the margins of the sheets were shaped and riveted together to function as hollow carlines. While this construction is highly meritorious, the amount of riveting that it requires makes it expensive, in the first instance, and particularly difficult and expensive to repair. Accordingly, it is the principal object of the present invention to devise a construction which will approximate the advantages of lower first cost and much greater facility of repair. The invention consists principally in a seam construction wherein the marginal portions 15 of adjacent sheets are formed into hollow ribs or inverted channels of different depths nested together and with a wooden filler interposed between them; also in securing said filler to said ribs separately by bolts which pass through said filler and some of which 20 pass through one rib and some through the other rib.

In the accompanying drawing wherein like reference numerals refer to like parts 25 wherever they occur,

Fig. 1 is a transverse section through a car roof embodying my invention, the section being taken between seams;

Fig. 2 is an enlarged transverse section 30 through one-half of the roof, the section being taken through one of the seams; and

Figs. 3, 4 and 5 are enlarged cross-sections 35 through one of the seams on the lines 3—3, 4—4, and 5—5, respectively in Fig. 2.

The accompanying drawing illustrates the roof portion of a car comprising angular side plates 1, and metal roof sheets 2, which span from side plate to side plate and have their end portions resting upon said side 40 plates, to which they are secured preferably by rivets 3. One side marginal portion of a roof sheet is pressed into the form of a comparatively low hollow rib 4 or shallow inverted channel of even height throughout 45 almost the full length of the sheet but having its end portions tapering to the plane of the sheet at the end thereof. The opposite marginal portion of said sheet is likewise formed into a hollow rib 5 or inverted chan-

nel whose end portion is higher than the low rib 4 of the first mentioned margin of the sheet and which increases gradually to a maximum height at the ridge of the car. Preferably the sheet is pressed from a rectangular blank, and the extreme marginal 55

portion 6 beyond the higher rib is left in the plane of the body of the sheet in the form of a horizontal flange whose width is greatest at the ends of the sheet and decreases to a minimum at the ridge where the 60 higher rib is of the greatest height. Both ribs or inverted channels taper somewhat upwardly and, in the plane of the body of the sheets the two ribs are of substantially the same width. By this arrangement, the 65 higher rib of one sheet will nest over the lower rib of an adjacent sheet of the same design so as to cooperate therewith after the manner of a carline.

In order to stiffen and strengthen the 70 seam construction, a wooden filler strip or strips 7 of pyramidal form are used in such space. Such filler strips or blocks are preferably first secured to the upper rib 5 by means of bolts 8 which extend downwardly 75 through the top of the upper rib and the filler blocks and are secured by nuts 9 threaded onto the lower ends of said bolts, the lower surface of said blocks being recessed so that neither the nuts nor the bolts 80 will project below the lower surface of such blocks. One such bolt near the ridge on each side thereof and another near each eaves portion of the car (four in all) are sufficient to secure the filler to the upper 85 rib. The filler blocks are secured to the lower ribs 4 in a similar manner: that is, bolts 10 whose heads lie in recesses in the upper surface of the filler blocks extend downwardly through said filler blocks and 90 the tops of the lower ribs and are secured by means of nuts 11 on the projecting threaded ends of such bolts. In this case also, one bolt near the ridge on each side thereof and another near each eaves portion 95 of the car (four in all) are sufficient to secure the filler block to the lower rib. Obviously, in the arrangement described, the last mentioned set of bolts should be passed through the filler block before the first mentioned bolts; but a different sequence of operations might result from a different arrangement of fasteners.

Preferably the bolts that extend through the top of the upper rib serve to hold the 105 running board saddle 12 which, in the form shown, comprises a sheet metal plate of Z-section, with the lower flange 13, through which the securing bolts extend, inclined to conform to the pitch of the roof, and 110

with the top flange 14, which supports the running board 15, disposed longitudinally.

Although the seam construction hereinbefore described may not be as strong as the 5 construction wherein the hollow ribs are rigidly riveted, the present seam construction approximates the advantages of such riveted construction, as the filler strip prevents the buckling of the metal and enables the ribs to 10 operate conjointly after the manner of a beam and develop the strength necessary for beam action. Aside from its economy of first cost, the present seam construction has the great advantage of facility and cheap- 15 ness of repair; for, to replace a sheet, it is unnecessary to shear any rivets (which entails risk of endangering the sound sheet) and there is no need for any riveting apparatus in making the replacement.

20 2. What I claim is:

1. A seam construction for car roofs comprising hollow ribs formed in the margins of adjacent sheets, said ribs being of different heights and nested together with a 25 filler member interposed between them.

2. A seam construction for car roofs comprising hollow ribs formed in the margins of adjacent sheets, said ribs being of different heights and nested together with a 30 filler member interposed between them, said filler member being secured to the upper sheet by fasteners that are wholly above the lower sheet and to the lower sheet by fasteners that are wholly below the upper sheet.

35 3. A car roof comprising roof sheets extending from side to side of the car and

having their side marginal portions formed into hollow ribs that nest together, the upper rib being higher than the lower rib and the space between them being occupied 40 by a filler to which each rib is secured separately.

4. A car roof comprising roof sheets extending from side to side of the car and having their side marginal portions formed 45 into hollow ribs that nest together, the upper rib being higher than the lower rib and the space between them being occupied by a filler to which each rib is secured separately, the means for securing said ribs 50 respectively to said filler constituting the sole means for securing said ribs together.

5. A car roof comprising roof sheets extending from side to side of the car and having their side marginal portion formed into 55 hollow flat-topped ribs with upwardly converging sides, the sides of the upper ribs fitting against the sides of the lower ribs but the tops of said ribs being spaced apart.

6. A car roof comprising roof sheets extending from side to side of the car and having their side marginal portions formed 60 into hollow ribs that are lapped to form seams, the lower ribs being of substantially uniform height from end to end of the sheets 65 and the upper ribs being of greater height at the ridge of the car than at the eaves thereof.

Signed at New Kensington, Pa., this 16th day of April, 1926.

CHARLES DAVID BONSALL.
